ROLLER VANE PUMP

Donald M. Lawrence, New Hartford, N.Y., assignor to
The Bendix Corporation, a corporation of Delaware
Filed Feb. 2, 1962, Ser. No. 170,551
5 Claims. (Cl. 103—118)

This invention relates to pumps and more particularly concerns a rotary pump in which rotor means traverses a profiled stator.

In prior constructions of roller-vane pumps (such as disclosed in the U.S. Patent #2,378,390, issued to Bertea), it was necessary to radially align the stator openings with the inlet and outlet in other structure. The provision of passages to and from its two pump chambers involved multi-part structure having several connecting passages and sealing means for mating openings.

An object of the present invention is to provide a rotary pump construction in which the disadvantage of radial alignment between stator openings and the inlet and outlet means of adjacent structure is avoided.

A further object is the provision of an improved rotary pump construction in which the flow is from an annular inlet chamber at one side of a stator through the pressurizing means to an annular outlet chamber at the other side of the stator.

A further object is to provide such a pump construction which is especially compact and easy to assemble due to the arrangement of few parts providing the inlet and outlet chambers.

Another object is to provide an improved roller-vane pump with a double profiled stator having a simplified, non-aligned construction which gives annular inlet and outlet chambers at each side of the stator, rather than connecting passages, and has a simple seal in the periphery of the rotor to prevent leakage from the outlet chamber to the inlet chamber.

The realization of the above objects along with the features and advantages of the invention will be apparent by reference to the accompanying drawing in which:

FIGURE 1 is a longitudinal cross-sectional view of a double-profiled, roller-vane pump embodying the invention and shows the upper half of the stator rotated ninety degrees in order to illustrate an outlet from a pump chamber so that flow from an annular inlet chamber to an annular outlet chamber is suggested, and

FIGURE 2 is an enlarged view of the discharge side of the pump stator and rotor and shows two crescent-shaped chambers, rollers urged out from grooves in the rotor to contact the profiled surfaces of the pump chambers and an inlet and an outlet in radial planes to each chamber.

Referring to the drawings, 11 indicates an electric motor connected by shaft 13 to the rotor 15 surrounded by stator 17 mounted in housing bore 19. Shaft 13 has a transverse slot 21 receiving a connecting pin 23, the ends of which are received in holes in rotor 15. Housing 27 has a threaded inlet 39 connected to the middle part of the bore 19 and a threaded outlet 30 connected through the bottom or closed end of the bore 19.

In the open end of bore 19, adjacent motor 11, a cup-like member 31 is mounted. The cup-like member 31 has a reduced-diameter axial projection 33 at the right which provides with housing bore 19 an annular inlet chamber 35 at the location of housing inlet 29. The axial projection 33 also has an axial bore 37 for receiving and supporting shaft 13. The annular transverse face of projection 33 abuts the inlet face of stator 17 at the inner part thereof for sealing and faces inlet side of the annular rotor 15. Cup-like member 31 has an annular side wall 39 contacting bore 19 at the open end and has inwardly of wall 39 a seal recess 41. Wall 39 has seal rings 43

2

which prevent leakage toward the motor 11 along wall 39. Seal recess 41 has two seal rings 45 which prevent leakage along shaft 13. The parts within bore 19 are held therein and urged toward the bottom by means of 5 annular plate 47 which is urged to the right by screws 49 threaded into the transverse part of the housing 27 surrounding the open end of bore 19.

Housing 27 is also provided with a by-pass 51 extending from outlet 30 to inlet 29. By-pass 51 is normally closed 10 by the adjustable spring-biased valve 53 to prevent return of liquid unless a predetermined pressure is exceeded.

The annular stator 17 has both its circular inlet edge 61 and its circular outlet edge 63 beveled. An inlet passage 65 extends from the bottom part of inlet edge 61 axially 15 to the middle or the mid-point section of the inner surface of stator 17 to provide communication of a pump chamber with the annular inlet chamber 35. At the right of stator 17, a seal plate or disc 67 is positioned and this disc has a recessed corner 69 facing the stator 17 to provide 20 an annular discharge chamber 71. Seal 72 in the stator periphery prevents leakage between the inlet and outlet chambers. An outlet passage 73 which is also axially-inclined extends from the axial center part or mid-point section of the inner surface of stator 17 to the 25 beveled outlet edge 63 for discharge from a pump chamber. As mentioned, it is to be realized that the stator having outlet passage 73 is actually rotated ninety degrees in order to suggest the flow path through the pump. As will appear, another inlet actually is opposite the inlet 30 which is shown. Alignment disc 67 has a flat transverse surface which abuts the outlet face of the stator 17, inwardly of outlet passage 73 for sealing, and which faces the right or outlet side of the rotor 15. Disc 67 is also provided with a plurality flats 75 in its peripheral surface 35 so that discharged liquid can flow from the discharged chamber 71 to the outlet chamber 77 formed by outlet recess 79 in disc 67 and the bottom surfaces of bore 19. From outlet chamber 77, the liquid leaves the pump 40 through outlet 30 connected to the closed end of bore 19. The bottom of bore 19 has an axially-projecting boss 81 which abuts and spaces plate 67.

In FIGURE 2 which suggests the operation the known double-profiled roller-vane pump as viewed from the discharge side, it can be seen that the inlet passages 65 and 45 outlet passages 73 are opposite each other or on common diameters, a half-circle apart. Rotor 15 has six channels or grooves 87 which loosely receive six rollers 88. As is well-known, the rollers 88 will be urged outwardly as shown by centrifugal action and will act as vanes against 50 inner elliptical surface of the stator 17. From FIGURE 2, it can be realized that the inlet passages 65 are centered in a radial plane and extend from the inlet edge of the stator 17 to the inlet ends of the crescent-shaped pump chambers 89 and that the outlet passages 73 are centered in a radial plane which is perpendicular to the plane of the inlet passages 65 and extend outwardly from the outlet ends of the crescent-shaped pump chambers 89 to the outlet edge 63 of the stator 17.

In the operation of the invention, rotation of the motor 60 drive shaft 13 operates to drive the rotor 15. Rotation of the rotor will cause the rollers 88 to advance therewith and the rollers 88 under the urge of centrifugal force will be caused to move outwardly in the channels 87 so as to bear against and traverse the stator profile in sliding and 65 rolling contact therewith. The rollers having slightly less diameter than the width of the grooves will shift laterally therein according to the direction of forces imposed thereon, as described in detail in above-noted patent. An effective seal is provided between the openings 70 of intake and outlet passages 65 and 73 when the rollers 88 traverse the sealing contours since the rollers will be

held in close contact with such contours under the urge of centrifugal force and will be held in intimate contact with the leading sides of their channel 87 while traversing the sealing contours under the urge of fluid pressure.

As the rollers traverse the stator profile, they will act as vanes in effecting inflow of liquid from the annular inlet chamber 35 through the inlet passages 65 and its discharge through the outlet passages 73 to the annular outlet chamber 71. By this action, liquid supplied to housing inlet 29 will be pressurized and delivered past sealing disc 67 to housing outlet 30. O-ring seal 72 prevents leakage along the stator periphery.

It is to be noted that, since the cylindrical projection 33 of cup-like member 31 provides the annular inlet chamber 35 and the seal disc recess 69 provides an annular outlet chamber 71 with the stator inlets and outlets opening into these chambers at the inlet and outlet corners of the stator, there is no necessity for radial alignment of passages. Further, complicated structure and seals are avoided for providing dual flows to and from a double-profiled stator. It is apparent that few parts are required and that the parts are easily assembled and provide a compact pump with provision for face seals at the stator ends and for ring seals at other required locations.

It is to be understood that persons skilled in the art can make changes in the disclosed embodiment of the invention without departing from the invention set forth in the following claims.

What is claimed is:

1. A rotary pump comprised of:
a housing having an axial bore,
a ring-like stator mounted in said bore,
said stator having an inner pump chamber with a profiled surface,
a rotor mounted in said stator and having means for traversing said profiled surface,
said stator having a flat inlet side with an outer peripheral corner and a flat outlet side with an outer peripheral corner,
said stator having inclined inlet passage means extending from the peripheral corner of its inlet side within said stator to said profiled surface and having inclined outlet passage means extending from the peripheral corner of its outlet side within said stator to said profiled surface,
means cooperating with said bore and said stator to provide an annular inlet chamber at the outer peripheral corner of the inlet side of said stator and an annular outlet chamber at the outer peripheral corner of the outlet side of said stator,
said stator having a seal in its peripheral surface for preventing leakage along said bore between said outlet chamber and said inlet chamber, and
said means abutting the inlet side and the outlet side of said stator to seal said pump chamber.
2. A rotary pump comprised of:
a housing having an axial bore,
a ring-like stator mounted in said bore,
said stator having an inner pump chamber with a profiled surface,
a rotor mounted in said stator and having means for traversing said profiled surface,
said stator having a flat inlet side with an outer peripheral corner and a flat outlet side with an outer peripheral corner,
said stator having inclined inlet passage means extending from the outer peripheral corner of its inlet side within said rotor to said profiled surface and having inclined outlet passage means extending from the outer peripheral corner of its outlet side within said rotor to said profiled surface,
means having a cylindrical projection cooperating with said bore and said stator to provide an annular inlet chamber at the outer peripheral inlet corner of said stator,

a seal plate having a peripheral recess providing with said bore and said stator an annular outlet chamber at the outer peripheral outlet corner of said stator,

said stator having a seal in its peripheral surface for preventing leakage along said bore between said outlet chamber and said inlet chamber,

said cylindrical projection abutting said inlet side of said stator to provide a seal for said pump chamber, and

said seal plate abutting said outlet side of said stator to provide a seal for said pump chamber.

3. A rotary pump comprised of:

a housing having an axial bore,
a seal plate having a flat transverse surface mounted in the bottom of said bore,

a ring-like stator having a flat inlet face with a peripheral outer corner and a flat outlet face with peripheral outer corner,

said stator being mounted in said bore and having said outlet face abutting said flat surface of said seal plate, said stator having an inner pump chamber with a profiled surface,

a cylindrical rotor mounted in said stator and having means for traversing said profiled surface,

said stator having inclined inlet passage means extending from the peripheral outer corner of said inlet face within said stator to said profiled surface and having inclined outlet passage means extending from the peripheral outer corner of said outlet face within said stator to said profiled surface,

said rotor having a shaft projecting axially from the side opposite said seal plate,

support means mounted in said bore at the open end thereof and having a cylindrical projection extending to said stator,

said cylindrical projection having an axial hole supporting said rotor shaft and having a transverse annular seal surface abutting said inlet face of said stator,

said cylindrical projection having a smaller diameter than said stator so that with said bore and said stator inlet face an annular inlet chamber is provided at the peripheral inlet corner of said stator,

said seal plate having an annular recess facing the outlet peripheral corner of said stator so that with said bore and said stator outlet bore an annular outlet chamber is provided,

said stator having a seal in its peripheral surface for preventing leakage between said outlet chamber and said inlet chamber, and

means urging said support means, said stator and said seal plate together so that seals are provided at flat contacting surfaces to prevent leakage from said pump chamber.

4. A rotary pump comprised of:

a housing having an axial bore,
a ring-like stator mounted in said bore and having a flat inlet face with an outer peripheral corner and a flat outlet face with an outer peripheral corner,

said stator having an inner pump chamber with a double-profiled surface,

a rotor mounted in said stator and having means for traversing said profiled surface,

means arranged to rotate said rotor,

said stator having two inclined inlet passage means extending from the peripheral corner of said inlet face within said stator to said profiled surface,

said stator having two inclined outlet passage means extending from the peripheral corner of said outlet face within said stator to said profiled surface,

first means in said bore providing with said bore and said stator an annular inlet chamber at the peripheral inlet corner of said stator,

second means in said bore providing with said bore

and said stator an annular outlet chamber at the outlet peripheral corner of said stator, said stator having a seal in its peripheral surface for preventing leakage along said bore between said outlet chamber and said inlet chamber, and said first and second means each having a flat surface abutting said stator to seal said pump chamber.

5

5. A roller-vane pump comprised of:

a housing having a bore, a ring-like stator positioned in said bore and having 10 a flat inlet side with a peripheral corner and a flat outlet side with a peripheral corner, said stator having a rotor chamber with two equally-profiled surfaces, a rotor having axial grooves and rollers loosely mounted in the grooves for traversing said two equally-profiled surfaces, 15 said rotor being mounted in said stator chamber, said stator having two inclined inlet passages connecting said bore to said rotor chamber for admission of fluid, 20 said inlet passages being diametrically located and each inlet passage extending from the inlet peripheral corner of said stator in radial plane to the mid-point section of the rotor chamber, said stator having two inclined outlet passages equally-spaced between said inlet passages, 25 each of said outlet passages extending from the outlet peripheral corner of said stator in a radial plane to the mid-point section of the rotor chamber whereby the fluid being pumped will move from the inlet side of said stator to the outlet side of said stator,

25
30

sealing means carried by said stator and contacting the side wall of said bore, motor means having an axial shaft connected to said rotor for causing said rollers to traverse said profiles by centrifugal action when said rotor is rotated by said motor means, tubular means mounted in said bore and having reduced-diameter section providing an annular inlet chamber, said reduced diameter section abutting the radially-inner portion of the inlet side of said stator to seal said rotor chamber and supporting said motor shaft, a sealing plate having a flat circular face abutting the outlet side of said stator inwardly of said outlet passages to seal said rotor chamber, said plate having a peripheral recess facing said stator at said outlet passages and providing with said bore and stator an annular outlet chamber, and passage means connected to said annular outlet chamber for discharge of fluid.
